UNITED STATES PATENT OFFICE.

REUBEN J. GRUBB, OF PHILADELPHIA, PENNSYLVANIA, ASSIGNOR TO JOHN BROMLEY & SONS.

DESIGN FOR A RUG.

SPECIFICATION forming part of Design No. 19,920, dated June 24, 1890.

Application filed May 27, 1890. Serial No. 353,378. Term of patent 3½ years.

To all whom it may concern:

Be it known that I, REUBEN J. GRUBB, a citizen of the United States, residing in the city of Philadelphia, State of Pennsylvania, have invented a certain new and original Design for a Rug, of which the following is a specification, reference being had to the accompanying drawing, forming a part hereof.

My invention relates to a design for the surface ornamentation of a rug, the accompanying photographic illustration of which will enable any one skilled in the art to make and use the same.

I claim as my invention—
A design for a rug, substantially as herein shown and set forth.

In testimony whereof I have hereunto affixed my signature this 22d day of May, A. D. 1890.

REUBEN J. GRUBB.
